UNITED STATES PATENT OFFICE.

JOHN R. ROGERS, OF BROOKLYN, NEW YORK, ASSIGNOR TO THE MERGEN-
THALER LINOTYPE COMPANY, OF NEW YORK.

LINOTYPE-MACHINE.

SPECIFICATION forming part of Letters Patent No. 669,400, dated March 5, 1901.

Application filed November 19, 1900. Serial No. 37,001. (No model.)

To all whom it may concern:

Be it known that I, JOHN R. ROGERS, of Brooklyn, county of Kings, and State of New York, have invented a new and useful Improvement in Linotype-Machines, of which the following is a specification.

My invention has reference to Mergenthaler linotype-machines and analogous machines, in which a series of metal matrices 10 having characters or matrices proper in one edge are delivered successively into an assembler or lining device, wherein they are assembled in line, side by side, with their characters in the order in which they are to 15 appear in print, so that when presented to a slotted mold they will form type characters in relief on the edge of the slug or linotype cast in such mold.

In practice it is found that each matrix approaching the line in a downward direction is liable to strike endwise against the side of the preceding matrix, and thereby indent or injure the thin and delicate wall forming the side of the character or matrix proper. As a result of this defective characters are formed on the slug, and sometimes the metal flowing between the indented walls of the matrices will produce on the slug small fins or burs, which receive ink and carry it to the paper between the letters.

35 The aim of the present invention is to prevent the matrices from injuring one another in the manner above stated; and to this end it consists in an assembling mechanism adapted to engage and guide each descending matrix in such manner that its lower or forward end is held positively away from the preceding matrix until it has passed below or beyond the matrix character.

40 The invention may be embodied in many forms, and the details may be modified to suit the shape of the particular matrix employed.

In the accompanying drawings I have shown my invention in a form adapted for use in the 45 Mergenthaler linotype-machine now in general use and represented in United States Letters Patent Nos. 436,531 and 557,000. In this machine each matrix is provided with ears or shoulders protruding edgewise at the 50 upper and lower ends, and the matrices are

delivered successively onto an inclined belt, by which they are carried downward and delivered in front of a rotary star-wheel, by which they are carried forward one after another into an assembler or holder.

In carrying the invention into effect I provide the side walls of the throat through which the matrices enter the assembler with lips or ribs in such position that as each matrix descends its lower ears will ride against the stationary lips and be held thereby away from or out of contact with the preceding matrix until the end of the incoming matrix has descended so far that it can do no injury to the other, at which point the ears of the matrix pass below the retaining-lips, so that the matrix may be moved bodily forward and added to the line. 60 65

Except in the particulars hereinafter enumerated, the machine may be in all respects 70 of ordinary construction.

Figure 1 is a front elevation of the assembling mechanism of a linotype-machine with my improvement applied thereto. Fig. 2 is a perspective view showing the throat through which the matrices enter the assembler and the rear wall of the assembler in which the matrices are received, the space-band chute or conductor being detached in order to expose the other parts more clearly to view. 80 75

Fig. 3 is a perspective view of the same parts with one matrix in the position it occupies at the end of the line in the assembler and a second matrix descending behind it, the ears of the second matrix being held back by the lips. Fig. 4 is a perspective view of the parts shown in the preceding figure looking from the rear. Fig. 5 is a front elevation showing the form and location of the retaining-lips and the manner in which the matrix engages therewith. Fig. 6 is a similar view with the matrix in a more advanced position. Fig. 7 is a perspective view of one of the matrices looking toward the operative edge. Fig. 8 is a cross-section of the assembler looking in the direction from which the matrices enter the same. 85 90 95

Referring to the drawings, A A represent the matrices, of the usual form, each consisting of a thin metal plate of rectangular form 100

with protruding ears at the upper and lower ends and with one or more characters or matrices proper, *a*, in one edge.

B is an inclined traveling belt on which the 5 matrices are delivered from the magazine one after another and on which they are carried downward and delivered over the belt-supporting pulley C into the open end of the assembler or holder D, the successive matrices 10 being acted upon by a rotary star-wheel H, which crowds the growing line forward in order to leave room for the incoming matrices at the rear.

Up to this point the parts are substantially 15 of the ordinary construction, so that each matrix descending the belt has a tendency to shoot forward and downward until its end encounters the preceding matrix at the end of the assembled line.

20 In carrying my improvement into effect I fix to the front and rear walls of the throat through which the matrices descend, above the belt and star-wheel, the two retaining-lips E E', extending downward and forward 25 from the rear of the line in such position that, although the body of a descending matrix may pass freely between them, the ears on the lower end of the matrix will encounter the lips and sliding downward against them be 30 held back out of contact with the preceding matrix until it has descended to approximately its final position, whereupon the matrix-ears passing beyond the lower ends of the lips are released therefrom, so that the 35 matrix may be moved up against the one preceding.

I find that the best results are attained when the upper ends of the lips E are curved upward and backward, as shown, in such relation 40 to the carrier-belt and the pulley C that the upper ears of the matrix will pass over the upper ends of the lips, as shown in Fig. 5, and descend along their forward faces, as shown in Figs. 3, 4, and 6.

45 The two lips E may be made alike and extended downward to a common level; but it is preferred to make the lip which engages the rear edge of the matrix which contains the character or matrix proper longer than 50 the other lip, as shown in the drawings. The effect of this is to release the lip at one edge of the matrix before that at the other edge is released, and consequently the matrix is given a slight twisting motion in its descent, so that

55 the edge which bears no character may move forward into contact with the preceding matrix while the edge bearing the character or matrix proper is still distant therefrom, as shown in Figs. 4 and 6. It is found that by 60 giving the incoming matrix an oblique relation to the line the assemblage is facilitated and the danger of injury from contact between the matrices lessened.

It is to be distinctly understood that it is 65 not necessary to extend the lips E upward so far that the upper lips of the matrices will

override them and pass down on the front side; but this is recommended as giving the best results.

It will be perceived that with my mechanism 70 the lower end of the matrix approaching the line is held positively away from the matrix in advance until the end of the moving matrix has advanced so far that it cannot contact with or injure the other. 75

In order to prevent the upper end of the descending matrix from being thrown forward too far or too quickly, so that it will stand in the path of the descending space-bars, I propose to use in some cases a side guide K, in 80 such position that the upper end of the matrix will ride thereunder, as shown in Figs. 4 and 6. This guide is preferably elastic and secured by a screw *k* at its upper end to the fixed portion of the frame. 85

What I claim as my invention is—

1. In a composing mechanism for linotype and analogous machines, an assembler to receive the matrices, and a stationary stop located in the path of the incoming matrices 90 and adapted to hold the lower end of each matrix positively out of contact with the preceding matrix until it has passed the character or matrix proper in such preceding matrix. 95

2. In a composing mechanism for linotype or analogous machine, an assembler to receive the matrices, means for delivering them successively thereto and assembling them in line therein, and fixed means for positively 100 holding each of the incoming matrices out of contact with its predecessor until it has reached approximately its final position.

3. In a linotype having matrices with ears or projections thereon, an assembling mechanism provided with a guide or lip to engage the matrix-ears and prevent contact between the matrices as they are added successively to the line. 105

4. In a linotype or analogous machine, the 110 throat or guide through which the matrices are delivered successively into an assembler, and stationary lips or guides on said throat to engage the opposite edges of the incoming matrices, substantially as and for the purposes described. 115

5. In a linotype having matrices with ears thereon, the assembling mechanism provided with lips adapted to engage the front and rear shoulders at the lower ends of the matrices, 120 substantially as and for the purpose described.

6. In a linotype-machine, a composing mechanism having the stationary lips or shoulders E E', constructed and arranged substantially as described, to direct the lower ears of the matrices downward on one side of the lips, while the upper ears of the matrices are caused to descend on the opposite side of said lips. 125

7. In a linotype-machine having the matrices with lips or shoulders thereon, means 130

adapted to coöperate with said shoulders to guide the successive matrices to the end of the composed line and hold the lower end of each matrix out of contact with its predecessor until it has nearly reached its final position, as described.

8. In an assembling mechanism for matrices, the combination of two guides, E and K, arranged to act respectively under and

over the matrix - ear, substantially as described.

In testimony whereof I hereunto set my hand, this 13th day of November, 1900, in the presence of two attesting witnesses.

JOHN R. ROGERS.
